ROTARY MASHER

René Charles Roi, Paris, France, assignor to Société Civile d'Etudes pour la Fabrication de Produits Industriels Manufactures (S. E. P. I. M.), Paris, France, a corporation of the French Republic

Application August 31, 1949, Serial No. 113,320
In France September 21, 1948

6 Claims. (Cl. 146—175)

1

It is known that mashers generally comprise a container provided with a perforated bottom acting as a sieve and through the center of which passes the axle of a crank handle made integral with a compression member of the helical type a generatrix of which is resiliently maintained in contact with said sieve.

It has already been proposed to substitute a comparatively thin plate for the bar generally used in combination with a coil-spring for applying the compression member into contact with the sieve. This plate has in its medial portion a perforated hole provided for passing the axle of the crank-handle through it, said hole being preferably located below the points where the plate is attached to the container, while the crank-handle has a stop against which the medial portion of the resilient plate applies and exerts its pressure.

This device has a few drawbacks because:

1. The perforated hole corresponding to the passage of the crank-handle decreases the strength of the plate at the location where the stretch is maximum.

2. The small thickness of the plate, which is necessary for obtaining a certain elasticity, enables to obtain only an imperfect guiding of the crank-handle's axle.

3. The flap dipping in the container for preventing the matter which should pass through the sieve of being rotatably driven provides only one shearing of said matter when the crank-handle makes one revolution.

The improvements which are the object of my invention prevent the above drawbacks. They are characterized in that the resilient bar is made of a metal wire having an appreciable elasticity, spirally coiled up near its medial portion in order to make at least one whorl having an internal diameter smaller than the diameter of a stop provided on the crank-handle's axle.

The manufacture of the strip by means of a steel wire having a big diameter, corresponding to any suitable section, enables to obtain an extremely low cost, and a resistance to permanent deformation which is practically never exceeded. It would occasionally be possible to remedy any permanent deformation by making again the spring bent through another permanent deformation in the opposed direction with respect to that which had produced the decreased elasticity. Finally the embodiment comprising one or more whorls at the medial portion has an increased strength at this location.

A further object of the invention is to provide

2

a device of the above mentioned character in which the medial whorl or whorls has or have an internal diameter which is equal, with the exception of the clearance, to the diameter of the crank-axle which is journalling in it or them.

Because of that arrangement, the whorls make a real bearing which ensures the centering of the axle.

A further object of the invention is to provide a device of the above mentioned character, in which the attaching means of the resilient bar are carried by the internal wall of the container and set at the lower portion of the latter.

The bar then fulfills the same purpose as that of a diametrical knife which avoids having a flap as it is the case at the present time and has with respect to said flap the advantage of ensuring a double shearing when the crank-handle makes one revolution.

Other objects and advantages of the invention will be apparent during the course of the following description.

In the accompanying drawing forming a part of this application and in which like numerals are employed to designate like parts throughout the same,

Fig. 1 is a perspective view of an embodiment of a masher comprising a resilient bar made of a metal wire according to the invention.

Fig. 2 is a partial elevational view showing the axle of the crank-handle carrying the compression member, and the bar made of a metal wire.

Fig. 3 is a section along III—III of Fig. 2.

Fig. 4 is a perspective view showing an embodiment of the locking device.

Fig. 5 is an axial section of a masher provided with a bar made of a metal wire set at the lower portion of the container.

Fig. 6 is a partial elevational view of the axle carrying the compression member and the resilient bar.

Fig. 7 is an elevational view of a locking hook, and,

Fig. 8 is a section along VIII—VIII of Fig. 7.

The following description relates to a few embodiments of resilient bars used in mashers having predetermined shapes and having a compression member constituted by only one blade co-operating with a frusto-conical sieve. It is to be understood that these members may be generally used in all mashers and like apparatuses fulfilling the purpose of pressing, shearing and making the food pass through a sieve, whatever be their shape, cylindrical, frusto-conical or other, and whatever be the number and the shape

of the blades of the compression member and the shape of the sieve used in combination with the latter.

Fig. 1 is a perspective view of a masher comprising a cylindrical container 1 along the axis of which is rotatably mounted a crank-axle 2, at one end of which is a compression blade 4 of the helical type maintained into contact with the sieve which forms the bottom of the container, and at the other end is a knob 3.

According to an embodiment more particularly shown in Fig. 2 and 3, the axle 2 of the crank-handle comprises a shoulder 5 whose distance above the compression member is such that it substantially exceeds the superior level of the container when in the working position. Around said axle and above said shoulder is coiled, in order to form at least one whorl 7, a piece 6 of metal wire having a suitable resiliency (made of steel for instance) and one branch of which is preferably ending with a buckle 8 enabling to exert a downwards vertical pressure on the corresponding branch.

On the external wall of the container 1 are attached at diametrically opposed points and by means of any suitable process, welding for instance, two brackets ending with hooks 9 projecting above the edge of the container and having each an opposite direction. These hooks, which are destined to receive the two branches 6 of the resilient bar, are located below the level of the shoulder 5 of the axle in such a manner that the bar is bent to such an extent that the compression member 4 is applied against the sieve with a sufficient pressure.

The discarding is obtained by exerting a pressure on the buckle 8 as previously stated and consecutively relieving the two ends of the bar from the corresponding hooks.

In Fig. 4, the bar is made in the same way, and the locking means comprise two diametrically opposed grooves 10, provided in the wall of the container and preferably having each a jump at its upper ending portion in order to constitute a bayonet locking.

Fig. 5 is an axial section of a masher comprising a frusto-conical container ending with a cylindrical wall having an internal lip 16. The latter is designed for receiving a lip having the same shape of a frusto-conical sieve 17 provided with a hub 18 having a sufficient length for ensuring the centering of the axle 2. The latter (Fig. 6) has no medial shoulder but carries an abutment 2' just above the blade 4, and the two ends 6 of the metal wire are identical; they are destined to be set inside hooks 15 (Figs 7 and 8) which lock them. These two hooks are attached below the setting of the axle 2 on the blade 4, which setting forms the stop on which rests the whorl 7 of the bar.

In that position, the bar carries out a double shearing in the matter to be mashed when the crank-handle performs one revolution. The fact that it is made of a wire makes it easy to clean.

In the preceding examples the bar, in case it is made of a wire, forms the male member of the locking device, the female member of said locking device being integral with the container. On the other hand, when the bar is made of a spring plate, the female and male members are reversed. It is of course to be understood that the above examples are not limitative, and that the same result would be obtained by reversing the purpose in view in each particular case.

It is also to be understood that the forms of my

invention herewith shown and described are to be taken as preferred examples of the same and that various changes in the shape, size and arrangement of parts may be resorted to without departing from the spirit of my invention or the scope of the subjoined claims.

What I claim is:

1. A masher, comprising in combination, an open top container having a perforated bottom wall; a crank having an abutment thereon and being rotatably mounted in said bottom wall of said container for rotation about an axis extending along the length of said container; a mashing member fixed to said crank for rotation therewith and being located just above said bottom wall of said container and below said abutment of said crank; and a one-piece, elongated, narrow, springy, cross member extending in a direction transverse to said axis of rotation across the interior of said container and being removably connected to opposite side wall portions thereof, said elongated, narrow, springy, cross member embracing said crank at a point just above said abutment thereof to resiliently urge the latter and said mashing member therewith toward said bottom wall of said container.

2. A masher, comprising in combination, an open top container having a perforated bottom wall; a crank rotatably mounted in said bottom wall of said container for rotation about an axis extending along the length of said container; a mashing member fixed to said crank for rotation therewith and being located just above said bottom wall of said container; and a one-piece, springy, wire member extending in a direction normal to said axis of rotation across the interior of said container and being removably connected to opposite side wall portions thereof, said springy, wire member embracing said crank at a point just above said mashing member to resiliently urge the latter and said crank therewith toward said bottom wall of said container.

3. A masher, comprising in combination, an open top container having a perforated bottom wall; a crank rotatably mounted in said bottom wall of said container for rotation about an axis extending along the length of said container; a mashing member fixed to said crank for rotation therewith and being located just above said bottom wall of said container, said mashing member being joined to said crank at a point located substantially midway between the top and bottom ends of said container; and a one-piece, springy, wire member located substantially midway between the ends of said container, extending in a direction normal to the axis of rotation across the interior of said container and being removably connected to opposite side wall portions thereof, said springy, wire member being bent only at a central portion thereof to form a loop embracing said crank at a point just above said mashing member to resiliently urge the latter and said crank therewith toward said bottom wall of said container.

4. A masher, comprising in combination, an open top container having a perforated bottom wall; a crank rotatably mounted in said bottom wall of said container for rotation about an axis extending along the length of said container; a mashing member fixed to said crank for rotation therewith and being located just above said bottom wall of said container; a pair of holding members each having a substantially U-shaped portion provided with an open end facing said bottom wall of said container and a closed end

facing the top of said container, said holding members being respectively fixed to opposite inner side wall portions of said container, and said U-shaped portions each being entirely spaced from said container side wall portions; and a one-piece, springy, wire member extending in a direction normal to said axis of rotation across the interior of said container and having opposite straight free ends respectively located beneath said closed ends of said U-shaped portions of said holding members, said springy, wire member being bent only at a central portion thereof to form a loop embracing said crank at a point just above said mashing member to resiliently urge the latter and said crank therewith toward said bottom wall of said container.

5. A masher, comprising in combination, an open top container having a perforated bottom wall removably mounted thereon, said perforated bottom wall being conical and having the apex thereof located within the interior of said container and the base thereof substantially coinciding with the bottom end of said container; a crank rotatably mounted in said bottom wall of said container for rotation about an axis extending along the length of said container and through the apex of said conical bottom wall; a mashing member fixed to said crank for rotation therewith and being located just above said bottom wall of said container, said mashing member being joined to said crank at a point located substantially midway between the top and bottom ends of said container; and a one-piece, elongated, narrow, springy, cross member located substantially midway between the ends of said container, extending in a direction transverse to said axis of rotation across the interior of said container and being removably connected to opposite side wall portions thereof, said springy, cross member embracing said crank at a point just above said mashing member to resiliently urge the latter and said crank therewith toward said bottom wall of said container.

6. A masher, comprising in combination, an open top container having a perforated bottom wall removably mounted thereon, said perforated bottom wall being conical and having the apex thereof located within the interior of said con-

tainer and the base thereof substantially coinciding with the bottom end of said container; a crank rotatably mounted in said bottom wall of said container for rotation about an axis extending along the length of said container and through the apex of said conical bottom wall; a mashing member fixed to said crank for rotation therewith and being located just above said bottom wall of said container, said mashing member being joined to said crank at a point located substantially midway between the top and bottom ends of said container; and a one-piece, springy, wire member located substantially midway between the ends of said container, extending in a direction normal to said axis of rotation across the interior of said container and having opposite straight free ends respectively located beneath said closed ends of said U-shaped portions of said holding members, said springy, wire member being bent only at a central portion thereof to form a loop embracing said crank at a point just above said mashing member to resiliently urge the latter and said crank therewith toward said bottom wall of said container.
